UNITED STATES PATENT OFFICE.

EDWARD J. BARRETT, OF NEW YORK, N. Y.

LOCK DEVICE FOR SHADE ROLLERS.

Application filed November 23, 1920. Serial No. 425,976. Renewed July 2, 1923.

To all whom it may concern:

Be it known that I, EDWARD J. BARRETT, a citizen of the United States, and residing at New York, in the county of New York and State of New York, have invented certain new and useful Improvements in Lock Devices for Shade Rollers, of which the following is a specification, such as will enable those skilled in the art to which it applies to make and use the same.

This invention relates to means for supporting shade rollers in position in a window frame and for locking the same against accidental displacement therein, and the object of the invention is to provide a device of this class which is simple in construction and operation and efficient in use, and which is constructed as hereinafter described and claimed.

The invention described and claimed herein is an improvement on that described and claimed in a prior patent granted to me August 14, 1917, No. 1,236,393, and the invention is fully disclosed in the following specification, of which the accompanying drawing forms a part, in which the separate parts of my improvement are designated by suitable reference characters in each of the views, and in which:

Fig. 1 is an inside view of the top portion of a window frame and indicating one use of my improved lock device;

Fig. 2 a partial section on the line 2—2 of Fig. 1 and on an enlarged scale;

Fig. 3 a partial section on the line 3—3 of Fig. 2;

Fig. 4 a partial section on the line 4—4 of Fig. 2;

Figs. 5, 6 and 7 are detail face views of the separate parts of my improved lock device; and,

Fig. 8 a partial section on the line 8—8 of Fig. 2 and showing a modification.

In Fig. 1 of the drawing I have indicated at 10 the top portion of a window frame and at 11 the side portions of said frame between which a shade roller 12 is mounted. The shank 13 at one end of the shade roller is mounted in a suitable keeper 14 while the shank 15 on the other end of said roller is mounted in one of my improved lock devices 16.

The lock device 16 comprises a suitable casing 17 which, in the form of construction shown, is oblong and rectangular in

general form and comprises a front plate 18 and inwardly directed side plates 19 forming a chamber 20. The upper end of the front plate 18 is provided with an aperture 21 which opens upwardly therethrough. The side plates 19 are provided adjacent to the upper end thereof with laterally directed ears 22 through which nails, screws or similar devices 23 are passed into the side members 11 of the window frame in securing the casing 17 in position.

A spring member 24 is mounted within the casing 17 and between said casing and side member 11 of the window frame, said spring member comprising an enlarged head portion 25 having apertures 26 through which the attaching devices 23 pass in securing the spring member in position. The spring member 24 is provided with a reduced central portion 27 and a finger piece 28 which normally projects through and beyond the lower end of the casing 17 as shown in Figs. 2 and 3 of the drawing, and the finger piece 28 and the spring member 24, or that portion thereof which is located within the casing 17, is provided with an aperture 29.

I also employ a lock plate 30 which is oblong and rectangular in form as is shown in detail in Fig. 7. The lower end portion of the plate 30 is fashioned to form an inwardly projecting lug 31 and the upper end portion of said plate is provided with an aperture 32 adapted to receive the shank 15 of the shade roller 12 as clearly shown in Figs. 2 and 3 of the drawing.

In the use of my improved lock device, as shown in Figs. 1 to 7 inclusive, the spring member 24 is first located upon the side member 11 of the window frame and the lock casing 17 placed thereon, after which the nails or screws 23 are passed through the ears 22 and the apertures 26 of the head member 25 to secure the separate parts of the lock device in position, after which the lock plate 30 is placed within the chamber 20 of the casing 17 by passing the same downwardly through the upper end of said casing and, in this operation, said plate is guided in its downward movement by two inwardly directed members 33 bent inwardly from the side plates 19 of said casing, as clearly shown in Figs. 3, 4 and 6 of the drawing. It will be noted that in the downward movement of the lock plate 30 the pro-

jecting lug 31 thereof will pass downwardly over the central portion 27 of the spring member 24 and into the aperture 29, and be retained in a locked position by said 5 spring member as is clearly illustrated in Fig. 3 of the drawing, and by forcing said spring member inwardly by a finger bearing upon the finger piece 28 thereof, the same may be released from the lug 31 to 10 permit of the detachment of the lock plate 30 of the casing 17. It will also be apparent that by forcing the finger piece 28 inwardly to rest upon the side member 11 of the window frame the lock plate 30 may 15 be passed through the lower end portion of the casing 17, if desired.

In the construction shown in Figs. 1 to 7 inclusive, the casing 17 and the spring member 24 are independent of each other and 20 are not intact prior to their mounting on a suitable support. In order to avoid this I may, if desired, secure said parts together when not in use by simply folding flaps, or the like 34 and 35 cut from the spring member 24 over the ears 22 of the casing 17 as 25 shown in Fig. 8 of the drawing, all of the parts being apertured as indicated at 38 in said figure to permit of the passage of the screws, nails or the like 23 therethrough in 30 securing the lock device in position.

It will be understood that while I have shown my improved lock device mounted in connection with the shank at one end of the shade roller 12, I am not necessarily limited 35 to this use, nor am I necessarily limited to the specific form and construction of the various parts of the lock device herein shown and described, and various changes in and modifications of the details of construction 40 may be made, within the scope of the appended claims, without departing from the spirit of my invention or sacrificing its advantages.

Having fully described my invention, 45 what I claim as new and desire to secure by Letters Patent, is:-

1. A device of the class described comprising a suitable casing open at the top and bottom, a spring member within said casing and extending through the lower end thereof to permit of the operation of said spring member, a lock plate detachably mounted in said casing, and means on said lock plate in connection with which said 50 spring member operates for retaining said lock plate against accidental displacement in said casing.

2. A lock device for the shank of shade rollers, comprising a casing open at the top and bottom, means detachably mounted in said casing and adapted to engage the shank of a shade roller for retaining said shank in said casing, and a spring member in said casing and extending through the lower end 60 thereof and in operative connection with said

member for retaining said member against accidental displacement in said casing.

3. A lock device for the shank of shade rollers comprising a casing open at the top and bottom and provided with an aperture 70 through which the shank of a shade roller is adapted to pass, a sheet metal plate mounted in connection with said casing and provided with an integral spring member located within said casing and extending through the lower end thereof to form a finger piece, and a lock plate adapted to be mounted upon the shank of a shade roller and detachably mounted in said casing and in connection with which said spring member 75 operates for holding said lock plate against accidental displacement in said casing.

4. A lock device for the shank of shade rollers comprising a casing open at the top and bottom and provided with an aperture 80 through which the shank of a shade roller is adapted to pass, a sheet metal plate mounted in connection with said casing and provided with an integral spring member located within said casing and extending 85 through the lower end thereof to form a finger piece, a lock plate adapted to be mounted upon the shank of a shade roller and detachably mounted in said casing and in connection with which said spring member 90 operates for holding said lock plate against accidental displacement in said casing.

5. A lock device for the shank of shade 95 rollers comprising a casing consisting of front and side plates, the front plate being provided at the top thereof with an aperture and the side plates with laterally directed ears through which attaching devices are 100 adapted to be passed, a sheet metal plate mounted in connection with said casing and through which said attaching devices are 105 also adapted to pass, said plate being provided with an integral apertured spring 110 member within said casing and which extends through the lower end thereof to form a finger piece, a lock plate adapted to be detachably mounted in said casing and provided with an aperture to receive the shank 115 of a shade roller, and means on said lock plate adapted to engage the aperture of said spring member for holding said lock plate against accidental displacement in said casing 120 for supporting said plate therein.

6. A lock device for the shank of shade 125 rollers comprising a sheet metal casing open at the back, top and bottom and provided with laterally directed attaching ears, a sheet metal plate comprising a cross head which forms a backing for the top portion of said casing and a depending spring member adapted to fit within the casing and extending through the lower end thereof, and a lock plate adapted to be mounted upon the 130

shank of a shade roller and detachably mounted in said casing and in connection with which said spring member operates for holding said lock plate against accidental displacement in said casing.

In testimony that I claim the foregoing as my invention I have signed my name in

presence of the subscribing witnesses this 22nd day of November, 1920.

EDWARD J. BARRETT.
